INVENTOR

ARTHUR WILLIAM SAVAGE
BY Milton E. Robinson

ATTORNEY.

UNITED STATES PATENT OFFICE.

ARTHUR WILLIAM SAVAGE, OF UTICA, NEW YORK, ASSIGNOR TO THE MAGAZINE HAMMER COMPANY, OF SAME PLACE.

MAGAZINE-HAMMER.

SPECIFICATION forming part of Letters Patent No. 653,890, dated July 17, 1900.
Application filed April 27, 1899. Serial No. 714,680. (No model.)

To all whom it may concern:

Be it known that I, ARTHUR WILLIAM SAVAGE, of Utica, in the county of Oneida and State of New York, have invented certain new and useful Improvements in Magazine Magnetic Tack-Hammers; and I do hereby declare that the following is a full, clear, and exact description of the invention, which will enable others skilled in the art to which it applies to make and use the same, reference being had to the accompanying drawings, and to the letters and figures of reference marked thereon, which form part of this specification.

My present invention relates to improvements in magazine magnetic tack-hammers. In the drawings, Figure 1 shows a side elevation of a tack-hammer of my improved construction. Fig. 2 shows the same with the handle portion in longitudinal section, exposing to view the working parts in the handle. Fig. 3 shows a partial section of the hammer-head and a partial section of the handle and magazine with the parts in their normal or out of operative position. Fig. 4 shows the same parts with the magazine omitted in the position which they assume after having been operated. Fig. 5 shows a rear view of the hammer-head with the parts in their normal position, in connection with a cross-section of the handle and parts located in the handle. Fig. 6 shows the same as Fig. 5 with the parts at the limit of movement after being operated. Fig. 7 shows an end or face view of the hammer-head and the parts adjacent to the face. Fig. 8 shows a perspective of certain of the operating parts in an intermediate position or during operation.

Referring to the reference letters and figures in a more particular description, 1 indicates the hammer-handle, and 2 the hammer-head, mounted thereon in the usual manner. One end of the hammer-head is recessed or cut away in order to receive the horseshoe or double-pole magnet 3, which is firmly secured to the head 2 and is held out of contact therewith by a sheet of insulating material 4. The magazine consists of a slotted tube 5, which extends along a recess in the under side of the handle and is curved down to a position on the side of the magnet

3, close to the face 6 of the magnet. The heads of the tacks are adapted to be received in the slotted tube, while the points project through the slot and from the magazine 5. The tacks are inserted in the magazine at a and are retained in the magazine by a spring 7, which operates to close this end of the magazine except against the placing of the tacks. The mouth or discharge end of the magazine is at b at the side and is substantially at right angles to the axial line of the head. For receiving the tacks from the mouth b of the magazine and moving them onto the face of the hammer or magnet 3 there is provided a reciprocating feeder-slide 8. The slide 8 is provided with a recess 9, the important part of which, however, is the shoulder 10 on the upper side. The recess 9 is adapted when the slide 8 is in its upper position to take a position at the mouth b of the magazine. The slide 8 is operated by a lever 11, pivoted at 12 in a recess in the handle and having the end adjacent to the head of the hammer engaging in a notch in the upper end of the slide 8. The lever 11 is also provided with an angular slot 13, in which engages a stud or pin 14, mounted on the sliding bar 15. The sliding bar 15 is provided with a finger-piece 16 and is operated on by a spring 17, located in a recess in the handle, which spring operates to force the bar 15 toward the hammer-head. The bar 15 at the end adjacent to the hammer-head is provided with a catch-shoulder 18, adapted to engage under a stud or projection 19 on the upper end of the slide 8. The upper end of the slide 8 extends into the slot in the hammer-handle, while the lower end of the slide is held and guided by a screw 20, passing through a slot 21 in the slide and engaging in the hammer-head. Pivoted on the screw 20 is also an automatic tack-holder 22, having a notch or recess 22a, as shown, adapted to take a position at the mouth b of the magazine, as shown. The automatic tack-holder 22 is operated by a projection or lip 23 on the slide 8, which engages on the cam-face 24 of the piece 22 and operates it in both directions. There is also provided a stop 25, against which the upper end of the piece 22 is adapted to strike, and its movement is limited in one direction there-

by. In the opposite direction the movement of the piece 22 is limited by the lower end coming in contact with the projection 3^a of one pole-piece of the magnet.

5 The operation of the device is substantially as follows: A quantity of tacks are placed in the magazine by inserting them at the opening *a*. When the hammer-handle is brought into a substantially-vertical position with the head downward, the tacks will slide or feed toward the head, and one of them will pass out of the mouth *b* of the magazine into the recess 9 in the end of the slide 8 and also into the recess 22^a in the end of the holder 22. 10 Tacks will also be fed toward the delivery end of the magazine by the centrifugal force when using the hammer for driving. When the tacks reach the delivery end of the magazine and have come under the influence of 15 the magnet, their heads follow the magnet closely. At the delivery end the tacks extend substantially at right angles with the hammer-head. When the operator desires to feed a tack onto the face of the hammer, he 20 operates the feeding mechanism by pulling on the finger-piece 16. This movement operates to throw the parts from the position shown in Figs. 3 and 5 to the position shown in Figs. 4 and 6. In this movement the shoulder 25 10 of the feeding device engages with the tack close to the head and slides it down the side of the magnet, and as the shoulder 10 is passed beyond the face of the magnet the head of the tack turns the angular corner between the face and side of the magnet or 30 head, while the point is forced over by the advancement of the shoulder 10 until by reason of the action of the magnet on the flat head of the tack, as well as by the momentum of the 35 point portion, the tack is brought into a line parallel with the axis of the head. In the face of one of the poles of the magnet there is provided a shallow recess *c*, through which one edge of the head of the tack passes, and as 40 the tack comes to its final position on the face of the magnet it squares itself over both poles, for the reason that as it comes into its final position the magnetic influence of both poles of the magnet reaches out for the tack and 45 causes it to assume this position. The final position of the tack on the magnet-head is indicated by the dotted circle in Fig. 7. Immediately after operation the parts are returned to their normal position by the operation of the spring 17, and the tack being properly located on the face of the magnet may be driven with one or more blows, as may be 50 found necessary.

When using the hammer for driving purposes, the tendency of the slide 8 to be projected or moved toward the face of the hammer in the direction of the blow under its own momentum is prevented by the shoulder 18 of the bar 15 engaging under the projection 19 on the slide 8. It will be noted, further, that in the operation of the parts the horizontal portion of the slot 13 in the part

11 allows the shoulder 18 to become disengaged from the projection 19 before the parts 11 and 8 begin their movement. The tack-holder 22 when the parts are in their normal position performs the office of entirely closing the discharge end of the magazine. It would not be entirely closed otherwise, for it will be noted that one shoulder of the recess 9 in the slide 8 is much smaller than the other, leaving an opening through which the tacks might escape if the holder 22 were not provided.

What I claim as new, and desire to secure by Letters Patent, is—

1. The combination with a hammer-head, handle and tack-magazine, of a tack-moving mechanism consisting of the slide 8 at the side of the head having a catch shoulder or projection, the lever 11 pivoted in the handle, engaging with the slide and having the slot 13, and the pull-bar 15 having a pin engaging in said slot 13, and a shoulder engaging with said catch-shoulder, substantially as set forth. 90

2. The combination with a double-pole magnetic hammer, of a magazine and tack-feeding mechanism arranged to deliver tacks onto the face of the hammer with the tack-heads partially upon each pole of the magnet, substantially as set forth. 95

3. The combination with a hammer of the horseshoe-magnet, the poles of which provide a driving-face and a tack guiding and feeding mechanism arranged to move the tacks with their heads substantially in the plane between the branches of the magnet whereby the tacks as they approach the face come within the influence of both poles and are delivered upon the face on each pole, substantially as set forth. 10

4. The combination with a magnetic hammer-head of a magazine arranged to deliver tacks adjacent to the face with the plane of the tack-head substantially at right angles with the plane of the hammer-face and a reciprocating feeding-slide movable lengthwise of the head and having a shoulder arranged to engage the body of the tack and movable substantially in a straight line to carry the shoulder from the side of the magazine-mouth more remote from the hammer-face to a point in advance of the face, substantially as set forth. 11

5. The combination with a magnetic hammer-head of a magazine having its mouth or delivery-opening at the side of the head adjacent to the face and formed to deliver tacks adjacent to the face, the tacks at the delivery end being in a plane substantially at right angles with the head, a tack-feeder operating along the side of the head across the delivery end of the magazine to a point beyond the face of the head, substantially as set forth. 12

6. The combination with a magnetic hammer-head having an angular corner as between the side and face of the head, a magazine with its mouth or delivery-opening at the side of the head adjacent to said angular

corner and arranged to deliver tacks at its mouth extending substantially at right angles with the hammer-head, and the tack-moving mechanism having a shoulder adapted to engage and move the tack from the mouth of the magazine and swing it onto the face of the head around said angular corner, substantially as set forth.

7. The combination with a magnetic hammer-head of a magazine having its discharge end or mouth adjacent to the face of the hammer-head, the feeding-slide 8 having the shoulder 10 operating across the mouth of the magazine to a point beyond the face of the hammer-head, the tack-holder 22 arranged to close the discharge end of the magazine and means for operating the slide and tack-holder, substantially as set forth.

8. In a hammer, the combination of a handle, a hammer-head, a tack-magazine, a movable tack-feeder operating in a plane parallel with the head and the sliding operating-bar arranged in the handle and adapted to engage said tack-feeder and secure the same against its own momentum, substantially as set forth.

9. In a magazine magnetic tack-hammer the combination of a magnetic head, a magazine terminating adjacent to the face of the head and to an angular corner between the side and face of the head and arranged to hold tacks adjacent to the face with the tack-heads in a plane substantially at right an-

gles with that of the face, and a tack-feeding mechanism having a shoulder adapted to operate from the discharge end of the magazine to a point beyond the face whereby the tacks are forced from the mouth of the magazine around the angular corner onto the face, and mechanism for operating said tack-feeding device, substantially as set forth.

10. The combination with a magnetic tack-hammer and its magazine, of a feeding-slide 8 having a stud or shoulder 19, the lever 11 engaging with the slide and pivoted in the handle and having an inclined slotted opening, the slide or pull-bar 15 having a projection engaging in said slotted opening and a shoulder engaging with said shoulder 19 on the slide 8, substantially as set forth.

11. The combination with a magnetic hammer of the magazine, the slide 8 operating across the mouth of the magazine and having a recess adapted to receive a tack at the end of the magazine, and a tack-holder 22 having a recess also adapted to receive a tack at the end of the magazine, and means for operating the slide and the tack-holder, substantially as set forth.

In witness whereof I have affixed my signature, in presence of two witnesses, this 25th day of April, 1899.

ARTHUR WILLIAM SAVAGE.
